US0D1044024S

(12) **United States Design Patent** (10) **Patent No.:** **US D1,044,024 S**
(45) **Date of Patent:** **** Sep. 24, 2024**

(54) **DIRECT SAMPLE COLLECTION PAD**

(71) Applicant: **ORASURE TECHNOLOGIES, INC.,**
Bethlehem, PA (US)

(72) Inventors: **Mark Fischl**, Bethlehem, PA (US);
Mark Emrick, Bethlehem, PA (US);
Keith Kardos, Bethlehem, PA (US)

(73) Assignee: **ORASURE TECHNOLOGIES, INC.,**
Bethlehem, PA (US)

(**) Term: **15 Years**

(21) Appl. No.: **29/871,229**

(22) Filed: **Feb. 15, 2023**

Related U.S. Application Data

(62) Division of application No. 29/780,671, filed on Apr. 26, 2021, now Pat. No. Des. 982,174.

(57) **CLAIM**

The ornamental design for a direct sample collection pad, as shown and described.

DESCRIPTION

FIG. 1 is a top view of a direct sample collection pad in accordance with our new design.

FIG. 2 is a top right perspective view of the direct sample collection pad of FIG. 1.

FIG. 3 is a bottom view of the direct sample collection pad of FIG. 1.

FIG. 4 is a left view of the direct sample collection pad of FIG. 1.

FIG. 5 is a left perspective view of the direct sample collection pad of FIG. 1.

FIG. 6 is a right view of the direct sample collection pad of FIG. 1.

FIG. 7 is a right perspective view of the direct sample collection pad of FIG. 1.

FIG. 8 is a top front perspective view of the direct sample collection pad of FIG. 1.

FIG. 9 is a front view of the direct sample collection pad of FIG. 1.

FIG. 10 is a top rear view of the direct sample collection pad of FIG. 1; and,

FIG. 11 is a back view of the direct sample collection pad of FIG. 1.

1 Claim, 11 Drawing Sheets
